US0D1006547S

(12) **United States Design Patent** (10) **Patent No.:** **US D1,006,547 S**
(45) **Date of Patent:** **** Dec. 5, 2023**

(54) **CONTAINER HOLDER**

(71) Applicant: **YETI Coolers, LLC**, Austin, TX (US)

(72) Inventors: **John Warren Dow**, Austin, TX (US);
Derek G. Sullivan, Austin, TX (US)

(73) Assignee: **YETI Coolers, LLC**, Austin, TX (US)

(**) Term: **15 Years**

(21) Appl. No.: **29/816,723**

(22) Filed: **Nov. 24, 2021**

Related U.S. Application Data

(62) Division of application No. 29/712,568, filed on Nov. 8, 2019, now Pat. No. Des. 938,785.

(57) **CLAIM**

The ornamental design for a container holder, as shown and described.

DESCRIPTION

FIG. 1 is a top, front, left perspective view of a container holder showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top, front, left perspective view showing our new design of FIGS. 1-7 in an exemplary environment.

The broken lines immediately adjacent to the shaded areas define the bounds of the claimed design and form no part thereof. The broken lines depicting features of the container holder form no part of the claimed design.

1 Claim, 7 Drawing Sheets
